UNITED STATES PATENT OFFICE

2,210,539

ELECTRIC SWITCH

Stanley Iwanowicz, Detroit, Mich.

Application February 25, 1939, Serial No. 258,451

1 Claim. (Cl. 200—159)

My invention relates to electric switches, and its principal object is to provide a switch mechanism of the push button type, more particularly for insertion into a wall and flush therewith, which is operable by means of a single push button which, by one movement, switches the current on and is returned automatically to the initial position, and then by a second movement in the same direction switches the current off and is again returned to the normal position, a construction which has many advantages over the present type of wall switch in which two separate buttons are employed for switching the current on and switching it off and also over the tumbler type of switch in which a single lever-like member is moved alternately upwards and downwards to produce the same results.

A further object of my said invention is to provide a switch in which a visible signal means is provided to indicate whether the switch is in the on or off position, such an arrangement being more especially desirable in the case of switches which control the supply of current to electric irons, washing machines, toasters, and other domestic appliances, many accidents and fires having occurred in cases where current has been inadvertently left on.

With these and other objects in view, I will now describe a preferred embodiment of my invention with reference to the accompanying drawing, in which—

Figure 1 is a front elevation of a wall switch constructed in accordance with my invention.

Figure 2 is a vertical section taken in general on the center line of the switch.

Figure 3 is a vertical section taken on line 3—3 of Figure 2.

Figure 4 is a horizontal section taken upon line 4—4 of Figure 2.

Figure 5 is a fragmentary vertical section taken on line 5—5 of Figure 4.

Figure 6 is a fragmentary diagrammatical view illustrating a modification of my said invention, and

Figure 7 is a front view of the push button employed in this modification.

Like characters designate corresponding parts throughout the several views.

In the drawing 1 designates the front cover or wall plate of the switch which is secured in position by screws 11 and has a rectangular opening 12 in which is slidably received the push button 2 of porcelain, glass, "Bakelite" or other non-conducting material. In the rear of the plate 1 is the vertically disposed frame 3 to which the

plate 1 is connected by the screws 11 and to the rear of this frame is the conventional switch box 4 which is generally made from porcelain. Within the box 4 are the upper and lower connectors 5, 6 held in position by screws 51, 61 which also serve as connecting means for the main feed wires 52, 62. Secured to the members 5, 6 as by rivets 53, 63 are the usual bifurcated contacts 54, 64.

Secured to or integral with the frame 3 are 10 guide members 31 of channel section in which are slidably received the guide plates 21 of the push button 2, and upon the rearward extremity of the members 31 are bearings 32 in which are rotatably mounted pivot pins 33. Upon these 15 pins are pivoted a U-shaped yoke 7 to which is secured an oscillatable contact member 8, the outer ends of which are adapted to pass between bifurcations of the contacts 54, 64 when the switch is in the on position, as shown in Figure 2. 20 Conversely, when the ends of the member 8 are disengaged from the bifurcated portions of the contacts 54, 64 the current is cut off.

In order to move the contact member 8 from the on to the off position and vice versa there is 25 provided upon the yoke 7 a rocker arm 9, the ends 91 of which are provided with V-shaped notches 91 as shown in Figure 2, and upon the push button 2 are mounted a pair of curved flat springs 22 which are arranged in V-shaped relation one to the other and have their ends so positioned as to engage in the notches 91 of the rocker 9. Transversely of the yoke 7 is a pin 71 30 with which engages one end of a helical tension spring 72, the other end of which passes over a pin 73 fixed to one of the guide members 31. 35

By reference to Figure 2 it will be observed that, the contact member being in the on position, the spring 22 is in a position to engage one of the notches 91 and when the push button is pressed inwards, the said spring will cause the rocker member 9, together with the yoke 7, to move about the pivots 33 and to disengage the ends of the member 8 from the contacts 54, 64, thus cutting off the current. The spring 72 is so arranged as to move the rocker 9 over the dead center in the manner well known in the art, so that by alternate inward movements of the push button 2 the current is alternately turned on and off as will be understood.

The ends of the springs 22 are so arranged that, when in their quiescent position, one of them is in alignment with a notch 91 of the rocker 9 when the switch is either in closed position, as shown in Figure 1, or in the open posi- 55

tion. As the rocker moves around its pivotal point, the engaged spring is held within its notch although the distance out from the median line increases. In the meantime, the free spring 5 passes within the adjacent end of the rocker and is there held until the push button is retracted, allowing the spring to escape and resume its initial position.

In order to provide a visible means to indicate whether the switch is in the on or off position, I have provided in the push button 2 an opening 23, and rearwardly of this opening is a small electric bulb 24 which is threaded re- 10 ceived in a socket 25 mounted upon the rear surface of the push button as by screws 26, the socket being grounded, and in order to supply current to this bulb there is a spring contact member 27 secured to the rear face of the push button as by screws 28. The socket 25 is connected by a wire, as shown, to the contact screw 55, and the member 27 is connected as by the wire shown to the contact screw 65, so that when the current is switched on the bulb is illuminated, and when the current is cut off the bulb 15 is dead. The bulb is preferably of red or other easily distinguishable color, and in order to easily replace the bulb 24 the push button 2 is split vertically into separate pieces 2A, 2B, the portion 2B being provided with notches 281 adapted to 20 receive the spring members 29 by which the two pieces are held together.

In the modification shown in Figures 6 and 7 of the drawing, I employ, instead of the light bulb 24, a segment 10 pivoted at 101 to the push button 2 and upon the circumferential face of this segment are the words "on" and "off" so arranged that the "on" and "off" condition of the switch are indicated and may be observed through the opening 102 in the push button. In 25 order to operate the segment 10 in synchronism with the yoke 7 and consequently with the contact member 8, the segment is provided with an extension 103 which is connected by a rod 104 to a bell crank lever 105 pivoted at 106 and connected by a link 107 to an arm 108 which forms 30 a part of the yoke 7.

It will be understood that the contact member

8 is insulated from the pivot 33 as by washers 81 and co-acting bushings in the well known manner. The return of the push button after each inward movement is effected by the springs 201 or by any equivalent means.

It will be observed from the foregoing description and by reference to the drawing that I have provided a simple and efficient device for carrying out the objects above recited, and while I have herein described and shown a preferred embodiment of my invention, it will be readily understood by those skilled in the art to which the same relates that various changes in detail may be made to suit any particular requirements without departing from the spirit of my invention 15 as defined in the appended claim. For example, while I have herein shown and described a push button of rectangular configuration, obviously I may employ other shapes, such as square, round, oval, or more ornamental and artistic forms as 20 hearts or diamonds. Furthermore, the push button may be formed from variously colored plastic materials having mirror-like, translucent or transparent properties, and where glass or other transparent material is used the openings design- 25 nated 23 and 102 may be dispensed with.

Having thus described my said invention, what I claim and desire to secure by Letters Patent of the United States is:

In an electric switch, the combination, with 30 a movable contact blade and a pair of fixed elements and connections arranged in cooperative relation therewith to form a circuit, of means for operating said blade to open and close said circuit including a rocker to which said blade is 35 secured, a second rocker operatively connected to said first-mentioned rocker and having notches in each end thereof, and means for operating said second rocker comprising a push button having thereupon a pair of spring members ar- 40 ranged in V-shaped relation and adapted to alternately engage in the notch of one or the other end of said rocker and to open and close said circuit, there being resilient means for returning said push button to its initial position. 45

STANLEY IWANOWICZ.
